UNITED STATES PATENT OFFICE.

BALDY ASHBOURNE CAPEHART, OF WASHINGTON, DISTRICT OF COLUMBIA.

FLY PAPER OR TRAP.

SPECIFICATION forming part of Letters Patent No. 761,202, dated May 31, 1904.

Application filed December 10, 1903. Serial No. 184,524. (No model.)

To all whom it may concern:

Be it known that I, BALDY ASHBOURNE CAPEHART, a citizen of the United States, residing at Washington, in the District of Columbia, 5 have invented certain new and useful Improvements in Fly Paper or Traps, of which the following is a specification, reference being had therein to the accompanying drawings.

This invention relates to improvements in 10 fly paper or traps, and has for its primary object the provision of a device which may be stored or shipped in the least possible space and which may be readily formed by the user into such shape as will protect the sticking or 15 poisonous substance on the inner face thereof from contact with extraneous objects should the device be upset or brushed against.

With the foregoing object in view a convenient embodiment of the invention embraces 20 a sheet of material carrying a sticky or poisonous substance on one face thereof, the same being adapted to be folded into a hollow formation with a plain or decorated exterior, and means associated therewith for 25 supporting the same when in use.

The novel details in the construction and arrangement of the several parts of the device will be apparent from the detailed description hereinafter when read in connection with the 30 accompanying drawings, forming part hereof, and wherein said embodiment is illustrated.

In the drawings, Figure 1 is an elevation of the treated side of a sheet or blank as it appears when marketed and prior to folding. 35 Fig. 2 is a perspective view of the sheet in its folded condition and as it appears when in use. Fig. 3 is a top plan view of Fig. 2, and Fig. 4 is a cross-section on the line 4-4 of Fig. 2.

Referring more specifically to the drawings, 40 wherein like reference characters designate corresponding parts in the several views, A designates a sheet or blank cut to any desired shape to fold into the predetermined hollow formation, the shape shown herein being substantially a sector whereby the blank when folded, Fig. 2, will form a cornucopia. The inner surface of the blank just referred to is coated with a sticky substance *a*, designed to entrap flies or other insects alighting thereon

or coming in contact therewith. This substance is so arranged that the same will be wholly confined within the device when folded, so that should the device tip over or be touched by extraneous objects the many objectionable characteristics of the ordinary 55 sticky fly-paper sheets are obviated. To properly secure the meeting edges of the blank when folded, any means found most practical or expedient may be employed. In the present instance I provide one edge of the blank 60 with a series of tongues or projections B, arranged to pass through slots *b* in the opposite edge of the blank and bent down thereupon, as best seen in Fig. 2. The tongues may be coated with mucilage or other adhesive material, whereby the same may be stuck to the exposed surface of the blank to more firmly secure the meeting edges against separation, as is obvious. I tie the extreme upper edges 65 of the sheet together through the medium of a wire C, carried by the upper edge of the blank, the projecting ends of the wire being twisted together, as at *c*.

While any convenient means may be utilized for the purpose of supporting the device, 70 it is preferable that some such means accompany and form a part of the blank when sold, and to this end I have devised a very efficient and simple device, comprising a wire D, fastened to one edge of the blank and depending 75 therefrom, the depending portion being bent into a circular or other shaped base E. While the device is being stored or marketed, the base E lies flat and in the plane of the blank or sheet, as shown in Fig. 1; and when the 80 device is in use said base is bent at right angles to the vertical axis thereof, as shown in Fig. 2. A supporting-base of this character—that is, one that may be bent from one position into another—is highly advantageous, inasmuch as it enables the blank to be dispensed in the same manner that the ordinary sticky fly-paper is sold, with the coated or treated surfaces of two sheets turned inwardly and opposing each other.

Although, as heretofore stated, the blank herein disclosed is coated with sticky material, I do not desire to be limited to its par-

ticular use, as in some instances a poisonous material supported upon the inside of the device will probably suffice, the nature of the entrapping or poisoning substance depending 5 upon the purpose for which the device is employed.

It is to be understood that slight changes and alterations in the device above defined may be made without in the least departing 10 from the spirit of the invention:

Having thus described the invention, what is claimed as new, and desired to be secured by Letters Patent, is—

1. A blank of the character described having 15 a sticky coating on its inner face and means at its upper edge for securing the same in folded condition closed at its lower end.

2. A blank of the character described a sticky coating on its inner face wired at its 20 upper edge whereby the same is retained in folded condition.

3. A wired blank of the character described a sticky coating on its inner face adapted to fold into a hollow formation, the wiring being 25 arranged to retain the blank in folded condition.

4. A single blank of the character described provided with a sticky coating on its inner face and also having projections adapted to 30 be interlocked to retain the same in folded condition closed at its lower end.

5. A blank of the character described provided with a sticky coating on its inner face and adapted to be folded into a hollow formation 35 having an open top and closed bottom, and also having projections adapted to be twisted together to retain the same in folded condition closed at its lower end.

6. A single blank of the character described 40 and having its inner face directly coated and adapted to be folded into a hollow formation closed at its lower end, the overlapping edges of the blank being devoid of the coating substance.

45 7. A single blank of the character described and having its inner face directly coated and adapted to be folded into a hollow formation closed at its lower end, the overlapping edges of the blank being devoid of the coating substance, and instrumentalities associated with 50 said overlapping edges for securing the same against separation.

8. A single blank of the character described and having its inner face directly coated and 55 adapted to be folded into a hollow formation closed at its lower end, the overlapping edges of the blank being devoid of the coating substance, and tongue-and-groove connecting in-

strumentalities associated with said overlapping edges for securing the same against separation. 60

9. In a device of the character described, a blank folded into a hollow formation, and means associated with the overlapping edges thereof for securing the same against separation, in combination with auxiliary retaining means at the upper edge of the blank. 65

10. In a device of the character described, a coated blank folded into a hollow formation closed at its lower end, and means integral 70 with the overlapping edges of the blank for securing the same against separation.

11. In a device of the character described, a coated blank folded into a hollow formation inclosed at its bottom, and tongue-and-groove 75 connecting instrumentalities formed with the overlapping edges of the blank for securing the same against separation.

12. In a device of the character described, a coated blank folded into a hollow formation 80 inclosed at its bottom, and means carried by the overlapping edges of the blank for securing the same against separation.

13. A blank of the character described adapted to be folded into a hollow formation, 85 and a support therefor carried thereby.

14. A blank of the character described adapted to be folded into a hollow formation, and a wire support therefor carried thereby.

15. A blank of the character described 90 adapted to be folded into a hollow formation, and a support therefor carried thereby, said support normally lying flat with the blank and adapted to be turned at right angles to its normal position when the blank is folded. 95

16. A blank of the character described adapted to be folded into a hollow formation, and a wire support therefor carried thereby, said support normally lying flat with the blank and adapted to be bent at right angles to its 100 normal position when the blank is folded.

17. A device of the character described comprising a blank folded into a hollow formation closed at its bottom, and a wire support 105 engaging the lower end thereof.

18. A device of the character described comprising a blank folded into a hollow formation closed at its bottom, and a support having a projecting portion fastened to the lower end thereof. 110

In testimony whereof I affix my signature in presence of two witnesses.

BALDY ASHBOURNE CAPEHART.
